(57) CLAIM

I claim the ornamental design for a bottle with an inserted jar, as shown and described.

DESCRIPTION

FIG. 1 is a top, front, right side perspective view of a bottle with an inserted jar showing my new design;

FIG. 2 is a front elevational view thereof;

FIG. 3 is a right side elevational view thereof; and,

FIG. 4 is a top plan view thereof.

1 Claim, 3 Drawing Sheets

FIG. 1
